UNITED STATES PATENT OFFICE.

CHARLES KAESTNER, OF CHICAGO, ILLINOIS.

BREWER'S MASHING-MACHINE.

SPECIFICATION forming part of Letters Patent No. 398,621, dated February 26, 1889.

Application filed August 20, 1888. Serial No. 233,167. (No model.)

To all whom it may concern:

Be it known that I, CHARLES KAESTNER, of Chicago, Illinois, have invented certain new and useful Improvements in Brewers' Mashing-Machines, of which the following is a specification.

My invention relates to certain improvements in a mashing-machine described in Letters Patent issued to me August 20, 1878, No. 10 207,283; and it has for its object the provision of such mashing-machines with means for adjusting the revolving mixer-shaft so as to raise the mixers from contact with the mash, and also the provision of means whereby to 15 similarly adjust the shaft which carries the shovels.

My present invention is an improvement upon appliances for lifting the mixer-shaft described in an application for Letters Patent filed by me April 7, 1888, Serial No. 20 269,960; and in an application for Letters Patent filed July 24, 1888, Serial No. 280,944, I have described means for rocking the mixer-shaft and shovel-shaft in their bearings, so as to hold the mixers and shovels out 25 of contact with the mash. In each of said several instances the mixer-arms and the shovel-arms are secured rigidly upon their respective shafts, and the central driving-shaft 30 is non-adjustable vertically and carries longitudinal arms rigidly secured thereon, from which the outer ends of the shovel and mixer shafts are supported.

In the accompanying drawings, Figure 1 is a 35 side elevation of the operative parts of a mashing-machine embodying my improvements, the mash-tub being shown in vertical section. In said figure the rakes and shovels are shown in full lines in their operative position, while 40 their elevated position is indicated by the dotted lines. Fig. 2 is a plan view of the operative parts of the machine, partly in cross-section, on the line *a b* of Fig. 1. Fig. 3 is a cross-sectional view of the driving-shafts on 45 the line *c d* of Fig. 1. Fig. 4 is an end elevation looking in the longitudinal direction of the revolving mixer-shaft. Fig. 5 is a cross-section on the line *e f* of Fig. 4.

In said drawings, 1 represents the wall of 50 the mash-tub; 2, the bottom thereof; 3, a dis-

charge-opening in said bottom, and 4 pipes for drawing off the wort.

5 is a vertical power-shaft located axially of the mash-tub and stepped into a fixed stud, 6, secured to the bottom of the mash-tub. 55

7 is an arm projected at right angles from the shaft 5, and having a depending hanger, 8, to support the outer end of the mixer-shaft.

9 is a mixer-shaft which has sliding journal-boxes, one of which, 10, is flanged to embrace and move upon the hanger 8, as shown in Fig. 4. The other journal-box, 11, is movable upon a central shaft carried parallel to the power-shaft 5, and has two bearings—one for the inner end of the mixer-shaft and the 60 other for the inner end of the shovel-shaft.

Each of the boxes 10 11 has a fixed nut, one of which is represented in 12 12, to engage the lifting-shafts. One of these shafts (designated by 13) is mounted at its upper end in 65 a suitable box, 14, and is carried parallel to the central driving-shaft, 5. Its lower end is exteriorly threaded and turns in the nut of the bearing 11. Said shaft carries bevel-gear 15, which communicates motion 70 through a bevel-gear, 16, to a shaft, 17, carried in suitable boxes parallel to the arm 7. Shaft 17 is adapted by means of bevel-gears 18 19 to impart motion to a second vertical shaft, 20, carried alongside the arm 8. 75 Shaft 20 has a threaded connection with the nut of the bearing 10. Shafts 13 and 20 have their exteriors threaded a sufficient distance to provide for the necessary adjustment of the mixer and shovel shafts. From this construction it is apparent that the turning of 80 the threaded shafts 13 and 20 will cause the lifting of the mixer-shaft by means of their threaded connection with the nuts 12, secured in the boxes 10 11. Motion will be imparted 85 to these threaded shafts 13 and 20 from a fixed gear, 21, secured at the top of the mash-tub upon a flange, 21^a, the latter being bolted to the mash-tub cover. This fixed gear 21 has a central opening, through which the shaft 5 passes. 90 A short vertical shaft, 22, is mounted parallel to the shaft 5, and carries upon its upper end a spur-gear, 23, which meshes with the fixed gear 21 and receives motion therefrom, and near its lower end it carries a second spur-gear, 23^a. 95 100

Said shaft has a bearing at its lower end upon a swinging plate, 24, which latter is pivoted near its middle on a bolt, 25. Said plate has a downwardly-curved arm, 26, to which is connected a shift-rod, 27, which, for convenience, may be extended longitudinally to the outside of the mash-tub, where it is provided with a handle, 28, whereby to manipulate it. The plate 24 carries a short shaft, 29, which has a spur-gear, 30, set thereon. The gear-wheels 23^a and 30 are set equidistant from the pivotal center of the plate and are adapted by the swinging of said plate upon its pivotal axis to be brought into mesh with a loose pinion, 31, which is slipped upon the central power-shaft, 5, and meshes with a spur-gear, 31^a, set on operating-shaft 13.

The swinging of the plate 24 is effected by an endwise movement of the rod 27, and the shaft 22 will be so secured in its upper bearing as to permit the slight deflection necessary to bring the gear on its lower end into mesh with the loose pinion on the shaft.

Supposing that it be desired to elevate the mixer-shaft from the position shown by the full lines, Fig. 1, to the position shown by the dotted lines of said figure, the plate 24 will be swung so as to throw the gear-wheel 23^a into mesh with the loose pinion on the shaft, 30, and then the shafts 13 and 20 will be turned in the proper direction to lift the mixer-shaft through the intervention of their threaded connections with the movable journal-boxes of said shaft. It will be understood that the mechanism for lifting the mixer-shaft will be duplicated for the purpose of raising the shovel-shaft.

I have applied to the hanger upon which the outer end of the shovel-shaft is journaled a rod, 32, having adjustable stops or collars 33 thereon and connected to an arm of the handle 28, whereby to automatically shift rod 27. The stops are so placed as to be engaged by the sliding journal-box at the upper and lower limits of its travel, and thus to throw the lifting device out of gear at the proper time.

When it is desired to lower the shafts, the plate 24 will be swung so as to throw gear-wheel 30 into mesh with the loose pinion on shaft 5, and the threaded operating-shafts will be turned in the opposite direction, causing the movable bearings to travel downward, and thus forcing the mixers and rakes gradually into the mash. This feature of the gradual insertion of the mixers and shovels constitutes an important feature of my present improvements; but there are other advantages in the construction herein explained—as, for example, in the rigid connections of the parts, whereby danger of breaking is avoided and certainty of action is secured.

It is apparent that the nuts 12 may be

made integral with the journal-boxes, or, in other words, that said boxes may have a threaded aperture to receive the threaded ends of the operating-shafts, and also that other gearing-connections may be employed. In order to allow the inner shovel to clear the driving-gear on the step 6, said shovel must be set at some distance from the step 6, and in order to operate upon the mash near the axial center of the machine I employ a supplementary shovel, 34, (shown in Fig. 1,) the arm of said shovel, 35, being connected by means of a bracket or collar, 36, with the shaft 5, so as to turn therewith. This shovel is so set as to throw or propel the mash out from the center, and thus assists not only in the mashing operation, but likewise in discharging the mash from the tub, and prevents the mash from piling up or clogging at the center of the mash-tub.

I claim—

1. In a mashing-machine, in combination with a non-adjustable central driving-shaft, a rigid arm extended longitudinally therefrom, vertical guides, one toward each end of said arm, a shaft carrying mash-working devices and having bearings movable along said vertical guides, operating-shafts having a threaded connection at one end with the movable bearings, and suitable gearing whereby to rotate the operating-shafts, substantially as described.

2. In a mashing-machine, the combination, with a longitudinal shaft carrying mash-working devices, of movable bearings for said shaft having threaded nuts, vertical operating-shafts, one for each bearing, said shafts adapted to turn in said nuts, whereby to move the bearings, and suitable gearing to rotate the operating-shafts, substantially as described.

3. In a mashing-machine, the combination, with the mixer-shaft and shovel-shaft having movable bearings provided with threaded nuts, of vertical operating-shafts threaded at one of their ends to adapt them to the threads of the bearings and suitable gearing whereby to rotate said operating-shafts and thereby simultaneously adjust the mixer-shaft and the shovel-shaft, substantially as described.

4. In a mashing-machine, the combination, with the mixer-shaft and shovel-shaft having movable bearings provided with threaded nuts, of vertical operating-shafts threaded toward one of their ends to adapt them to the threaded nuts of the bearings and a shifting rod having stops adapted to engage the movable bearing of one of the shafts, whereby to throw the operating-shafts out of gear, substantially as described.

CHARLES KAESTNER.
